UNITED STATES PATENT OFFICE

JOHN S. NORTON, OF SAN FRANCISCO, CALIFORNIA, ASSIGNOR OF ONE-HALF TO
WILLIAM F. HOLLINGSWORTH, OF SAN FRANCISCO, CALIFORNIA

WELDER'S HOOD

Application filed September 22, 1930. Serial No. 483,842.

My invention relates to improvements in welder's hoods, and it consists in the combinations, constructions and arrangements hereinafter described and claimed.

An object of my invention is to provide a welder's hood in which a hinged eyeglass is locked in closed position so as to prevent accidental movement, the lock, however, being first released by the mechanism that swings the glass into open position. The chin of the operator is used for actuating the mechanism.

The eyeglass is held in open position by a weighted trigger, and when the operator wishes to have the eyeglass closed by gravity, all this is necessary is to swing the head laterally and this will cause the weighted trigger to release the mechanism that holds the glass in open position.

A further object of my invention is to provide a device of the type described which is extremely simple in construction and which is durable and efficient for the purpose intended.

My invention is illustrated in the accompanying drawings, in which:

Figure 1 is a section along the line 1—1 of Figure 2.

Figure 2 is a front elevation of the device, Figure 3 is a rear elevation of the device, and

Figure 4 is a section along the line 4—4 of Figure 3.

In carrying out my invention I provide a welder's hood 1 of standard construction, this hood being supported by a head band 2. The front face 3 of the hood carries a frame 4 in which an eye shield mechanism is mounted.

This eye shield mechanism comprises a cover frame 5 hinged to the frame 4 at 6. An eye-protecting glass 7 (see Figure 4) covers an opening 8 in the frame 5 and is held in place by spring clips 9. A second glass 10 is disposed on the outside of the frame 5 and protects the glass 7. The glass 10 is held in place by spring clips 11 and supports 12.

The cover drops into closed position by gravity when the hood is held in the position

shown in Figure 1. An automatic catch 13 is used for preventing the frame 5 from swinging into open position until manually released. This catch is shown in Figure 4 and is rotatably mounted on a pin 14 carried by a flange 15 of the frame 4. The hook-shaped end 16 of the catch receives a pin 17 carried by the frame 5. A weighted portion 18a of the catch tends to hold it in the position shown in Figure 4 by gravity, and when the cover 5 swings into closed position, the pin 17 will momentarily swing the catch 13 in a counter-clockwise direction until the hook 16 rides over the pin, whereupon the weighted end 18a will cause the hook to engage with the pin. If, now, the face 3 of the hood is swung into substantially horizontal position, as is the case when the device is in use, the catch 13 will prevent the accidental opening of the cover 5.

I provide means for manually opening the cover 5, and this means first releases the catch 13 so as to free the cover. In Figure 3 I show a frame 18 having sides 19 and 20, the side 19 having a slot 21 therein (see Figure 4) for receiving one end of a rod 22, while the side 20 has an opening for receiving the other end of the rod 22. A spring 23 is secured to the top of the side 19 and holds the frame 18 in a slightly inclined position as shown in Figure 3.

A chin-actuated member comprising a rack bar 24 secured to the frame 18 and an adjustable chin rest 25 is used for actuating the frame 18. The frame has an opening 26 the upper edge 27 of which engages with an extended portion 28 of the catch 13. When the operator wishes to open the cover 5, he presses downwardly upon the chin rest 25, and this will cause an initial movement of the frame 18 to release the catch 13. At the moment of release, the rod 22 is moved to the top of the slot 21, and further movement of the frame 18 in a downward direction will move the rod 22 downwardly. The rod 22 is connected to arms 29 which in turn are secured to the cover 5. These arms swing the covers into open position as the rod 22 is moved downwardly.

I also provide automatic means for hold-

ing the cover in open position. Reference to Figure 3 shows a pin 30 as being carried by the frame 18, and this pin is engaged by a weighted trigger 31 when the cover 5 is in open position. The trigger 31 holds the cover 5 in this position. When the operator wishes to release the cover, he merely moves his head laterally and the weighted end 32 of the trigger 31 will swing the trigger free of the pin 30 and permit the cover to close by gravity. The cover is again held in closed position by the catch 13 in the manner already described.

It will be seen from the foregoing that the operator has complete control of the opening and the closing of the cover 5 and the device automatically locks the cover in either open or closed position.

Although I have shown and described one embodiment of my invention, it is to be understood that the same is susceptible of various changes, and I reserve the right to employ such changes as may come within the scope of the claims hereto attached.

25 I claim:

1. A welder's hood comprising an eye glass carrying frame hinged to the hood and swingable into closed position by gravity, a catch for locking the frame in closed position, and 30 manually controlled means for first releasing the catch and then for swinging the frame into open position.

2. A welder's hood comprising an eye glass carrying frame, means actuated by the chin 35 of the operator for opening the frame, means for holding the frame in open position, said holding means freeing the frame when the operator abruptly moves the hood in a transverse direction, and means for locking the 40 frame in closed position, said locking means being released when the frame opening means is actuated.

3. In a welder's hood, an eye glass frame hinged to the hood, a gravity actuated catch 45 for locking the frame in closed position, a chin actuated member connected to said catch for opening the catch, said member having a lost motion connection with the frame for moving it, this motion being employed for 50 first freeing the catch and then swinging the eye glass frame.

4. The combination with a welder's hood having an eye opening therein, of a glare shield normally covering the opening, a 55 weighted trigger for holding the shield in raised position, a pin carried by the shield and swinging the trigger into released position during the opening movement of the shield, said trigger when freed swinging into 60 a position to engage with the pin and support the shield in raised position, said trigger freeing the pin when the hood is moved abruptly in a lateral direction.

JOHN S. NORTON.
